UNITED STATES PATENT OFFICE.

WRIGHT DURYEA, OF BROOKLYN, ASSIGNOR TO THE GLEN COVE MANUFACTURING COMPANY, OF GLEN COVE, NEW YORK.

STARCH-DEPOSITING PLANE.

SPECIFICATION forming part of Letters Patent No. 320,430, dated June 16, 1885.

Application filed September 5, 1884. (No model.)

To all whom it may concern:

Be it known that I, WRIGHT DURYEA, of the city of Brooklyn, in the county of Kings and State of New York, have invented a new and useful Improvement in Starch-Depositing Planes or Runs, of which the following is a specification.

In order to separate or obtain the starch from the starch-milk, the latter, at a proper stage in its treatment, is caused to flow over or along planes or runs, on which the starch is deposited, while the spent liquor with the fine gluten still in suspension flows away from the end of the depositing plane or run. In order to obtain good results and insure the depositing of nearly all the starch, these planes or runs are often a hundred or more feet in length and have but a very slight inclination. When the depositing on the plane or run is commenced, the result is very satisfactory, but the starch is deposited much more rapidly and in much greater quantity near the head of the plane or run than near the tail end thereof, and the consequence is that as the plane or run fills up, the inclination of its bottom, owing to the uneven deposit of starch, becomes greater, the flow of the starch-milk becomes more and more rapid, and the quantity of starch which is not deposited, but which passes from the plane or run with the spent liquor or gluten-water, increases to a wasteful extent.

The object of my invention is to maintain a more uniform inclination of the planes or runs, whether they be full or empty, and to thereby increase the economy of the depositing operation.

To this end my invention consists in the combination of a series of comparatively short planes or runs, arranged one in advance of the other, with the tail of each resting on the head of the next, and a transverse partition in the head of each plane or run in advance of the first, and forming therein a weir, over which the starch-milk flows.

The invention further consists in the combination, with the series of planes or runs arranged and constructed as above described, of stirrers or agitators arranged behind the transverse partitions in the heads of the several planes or runs, and by their operation serving to

prevent the spaces behind said partitions from filling up.

In the accompanying drawings, Figure 1 is a sectional view of a series of planes or runs embodying my invention. Fig. 2 is a similar view on a larger scale, illustrating the tail portion of one plane or run and the head portion of the one next in advance. Fig. 3 is a plan of the parts shown in Fig. 2 and on the same scale; and Fig. 4 is a transverse vertical section on the plane of the dotted line *x*, Fig. 2.

Similar letters of reference designate corresponding parts in all the figures. 65

A A' A² designate depositing planes or runs, any number of which may be arranged in a series, as shown, one in advance of another, the tail of each plane or run resting upon and supported by the head of the run next in advance of it. The series of planes or runs is supplied from a tank or vat, B, as is usual. At the tail end of each plane or run is a gate, *a*, capable of vertical adjustment in suitable guides, *b*, by means of screw rods *c* and nuts *d*, in a well-understood manner. This gate is to be raised slightly from time to time as the plane or run fills up. In the head of each plane or run, except the first of the series, is secured a transverse partition, *e*, forming a weir over which the fluid flows to the plane or run, and behind this partition and in the head of the plane or run is a stirrer or agitator, *f*, which may be rotated slowly by a belt over a pulley, *f**, and which prevents starch from depositing behind the partition *e*. 85

I am aware that adjustable gates have been arranged at the tail ends of long depositing planes or runs, and that there has been arranged at the tail ends of such long planes or runs a gutter for receiving the spent liquor or gluten-water. These features I do not claim as of my invention. 90

By employing a number or series of comparatively short planes or runs arranged as described I am enabled to maintain a nearly-uniform inclination of the bottom of each, whether they be empty or partly filled, and in this way I secure a more even speed of flow and a more economical operation, with but little waste. 95 100

By interrupting the flow of the liquor in the manner described I also break up or stop the formation of eddies or currents in the liquor, and obviate to a great extent the guttering or formation of channels in the deposited starch, which all tends to produce waste.

5 The edge of the partition forms a clearly-defined and permanent horizontal weir, over which the milk flows in an unbroken line from side to side, and thus prevents the guttering or channeling of the deposited starch at the head of the plane or run.

10 What I claim as my invention, and desire to secure by Letters Patent, is—

15 1. The combination of a series of planes or runs, arranged one in advance of another, with the tail of each resting on the head of the next, and a transverse partition in the

head of each plane or run in advance of the first, and forming therein a weir, over which 20 the starch-milk flows, substantially as and for the purpose herein described.

2. The combination of a series of planes or runs arranged one in advance of another, with the tail of each resting on the head of 25 the next, transverse partitions forming weirs in the heads of said planes or runs, and stirrers or agitators for preventing the deposit of starch behind said partitions or weirs, substantially as and for the purpose herein de- 30 scribed.

WRIGHT DURYEA.
